Patented Dec. 5, 1911.

UNITED STATES PATENT OFFICE.

SURVILLE J. DE LAN, OF GLENWOOD SPRINGS, COLORADO.

DIRIGIBLE AIRSHIP.

1,010,483.

Specification of Letters Patent.

Patented Dec. 5, 1911.

Application filed March 8, 1911. Serial No. 613,068.

To all whom it may concern:

Be it known that I, SURVILLE J. DE LAN, a citizen of the United States, residing at Glenwood Springs, in the county of Garfield and State of Colorado, have invented a new and useful Dirigible Airship; and I do hereby declare the following to be a full, clear, and exact description of the invention, such as will enable others skilled in the art 10 to which it appertains to make and use the same.

This invention belongs to the art of aerial navigation, and more particularly pertains to a new and useful dirigible airship, and 15 the object of the invention is to provide a device of this design in which there is involved novel features.

The invention, in its broadest scope, aims as its primary object to provide an airship of 20 this design having two gas reservoirs spaced apart, with a housing of any suitable design and construction suspended between them. This housing may be supported with relation to the reservoirs, by any suitable framework, for instance, as shown in the drawing. 25 However, it is to be remembered that the applicant does not confine himself to any specific form of framework or housing, nor does he restrict himself to the exact relation 30 the housing assumes with regard to the reservoirs. The gas may be admitted to the reservoirs by any conventional method, therefore, no construction of valves or inlets are shown or described.

35 A further object, which is particularly essential, of the invention is the provision of gravitating aeroplanes or wings, suitably connected to the lower outer corners of the housing, in such a manner as to move freely, 40 and to assume substantially vertical positions with relation to the housing, as the craft is ascending. However, when the craft is descending, these aeroplanes or wings arrange themselves substantially in horizontal 45 planes, or nearly so, thus preventing the craft from making a quick dart downwardly. When the craft is traveling forwardly in an undulating line, that is, in an up and down direction, these aeroplanes or 50 wings slightly vibrate or oscillate by gravitation, thus maintaining the equilibrium of the craft. These aeroplanes, in practice, may be constructed of any suitable framework of any suitable material, and properly 55 covered with areas of canvas or the like, which may be supplied with a coating of

light varnish, in order to prevent the wind currents from percolating through the fabric.

The aeroplanes or wings may be any suitable shape, but, as shown in the drawing, are illustrated as being slightly bowed in directions at right angles, in order to permit the wind currents to roll or fold thereunder, thus assisting in holding the craft afloat in 60 the air. 65

The applicant does not confine himself to any specific form of connection between the wings or planes and the lower outer corners of the housing, for it is clearly apparent 70 that these connections may be any conventional form. However, the applicant has illustrated one form of connection, which embodies a hollow angular plate secured to the corner of the housing by bolts, and provided with means for limiting the wings or 75 planes in their movements.

It is not the purpose of this invention to provide propellers or other means for driving the airship or craft forwardly, rearwardly, or laterally, nor is it the object of this invention to provide means for rotating such propellers, or means for guiding or steering the craft laterally or vertically; therefore, these mechanisms are entirely 85 omitted from this application. In the drawings, however, there is only disclosed one form of the invention, but, in practical fields, this form may require alterations, to which the applicant is entitled, provided the alterations are comprehended by the appended 90 claims.

The invention comprises further features and combinations of parts, hereinafter set forth, shown in the drawings, and claimed. 95

In the drawings:—Figure 1 is a view in perspective of a dirigible airship or craft, the same being shown as in flight with the aeroplanes or wings shown substantially in horizontal planes. Fig. 2 is an end elevation of the craft, showing the planes or wings substantially in horizontal planes, in full lines, and in substantially vertical planes, in dotted lines, there being parts broken away on one side of the craft or airship, in order to illustrate the connections between the planes or wings and the housing. Fig. 3 is an enlarged detail sectional view through one of the connections of the planes or wings and the housing. 100 105 110

Referring to the annexed drawings, 1 designates two cigar-shaped reservoirs or

balloons which may, or may not, be covered upon their lower parts by a suitable netting, made of bamboo or cording, as shown at 2, while the upper portions of the reservoirs 5 or balloons may or may not be covered similar to the lower part, as will be understood from the drawings. However, there are bands 3 encircling the reservoirs, thus constituting means for holding them in 10 place, while there are bands 4 extending longitudinally of the reservoirs at their top portions, which are secured at the end extremities thereof, as shown at 5. 6 denotes a suitable housing, which may 15 be of any desired construction. The housing is provided with a lower chamber 6^a adapted to contain the machinery used in propelling, steering or guiding the ship or craft, and for transportation purposes. The 20 lower part of the housing is provided with an upper chamber 6^a of the housing to be open from end to end, as shown between the roof 6^b and floor 6^c, in order to utilize the current of air passing through the chamber 25 to aid in sustaining the craft on the aeroplane principle. Embracing this housing is a framework 7 which may be made of any suitable material or metal, such as aluminum or the like, in the form of tubular 30 rods if metal is used, which may be joined together by the couplings 8. The bands 3 connect to the couplings, as shown at 9. Embracing the lower outer corners of the 35 housing are angular plates or members 10, which are secured to the housing by any suitable means, as shown at 11. These plates are hollow, as shown at 12, and extending transversely through them are the pivot members 13, on which the hinge members 40 14 are pivoted. These hinge members 14 are provided with light extension members or arms 15 and 16, which embrace the aeroplanes or wings 17, upon their upper and lower faces. The extremities of these members 45 15 and 16 embrace the outer portions 18 of the frames 19 of the planes or wings, and are secured in place by bolts or other suitable means 20. The hinge members may be made of any suitable metal, for instance, 50 steel or the like, while the members or arms 15 and 16 are made of some light material, or other material for instance, aluminum or the like, and are connected to the hinge members 14, as at 21. The frames of the 55 planes or wings are made of any suitable tubular metal or other material, such as aluminum, and are rectangular in contour in plan view. However, these frames are bowed in two directions, as shown in the 60 drawings, and stretched over the frames are areas of fabric, such as canvas or the like 22, upon which above and below, coatings of light varnish are supplied, as shown at 23, which prevent the air currents from 65 percolating therethrough. The corners of

the frames are braced, as shown at 24, in order to prevent the frames from becoming distorted.

When a dirigible airship or craft is constructed substantially in accordance with the showing in the drawings, and supplied with gravitating aeroplanes or wings in the manner shown, flights of various heights may be accomplished. A craft of this character, when ascending, has its aeroplanes 70 or wings arranged substantially in vertical planes, but when descending, the planes assume substantially horizontal positions. The positions, however, vary considerably, it depending on the ballast of the craft, for 75 instance, if there is more weight upon one side of the housing than on the other, the positions of the wings or planes vary with 80 relation to one another.

From the foregoing, it will be clearly 85 noted that a novel form of dirigible airship or craft has been devised, and one which has been found to be practicable, in so far as the structure as shown in the drawing is concerned. The gravitating aeroplanes or 90 wings have been found to be a wonderful advancement in this particular art, that is, as applied to the craft, as shown in the 95 drawings.

The invention having been set forth, what 95 is claimed as new and useful is:—

1. In a dirigible airship or craft, a pair of gas reservoirs spaced apart, and a housing having a lower closed chamber suspended between the reservoirs, the lower chamber 100 adapted to contain the machinery used in propelling, steering the craft, and for transportation purposes, the housing having an upper chamber open from end to end, between the roof and floor, in order to utilize 105 the current of air passing through the upper chamber to aid in sustaining the craft on the aeroplane principle.

2. In a dirigible airship or craft, a housing, a pair of gravitating aeroplanes or 110 wings having hinged connections with the lower outer corners of the housing, adapted to assume substantially vertical positions when the craft is ascending, and substantially horizontal positions when the craft is 115 descending, said aeroplanes or wings adapted to be entirely free to vibrate or oscillate when the craft is traveling in an undulated line, said connections including means for 120 limiting the planes or wings in their substantially vertical and horizontal positions.

3. In a dirigible airship, a housing, a pair of gravitating aeroplanes or wings connected to the lower outer corners of the housing, 125 adapted to assume substantially vertical positions when the ship is ascending, and substantially horizontal positions when the ship is descending, the wings adapted to be entirely free at one end to vibrate freely by gravitation between the vertical and hori- 130

zontal positions, when the ship is traveling in an undulated line.

4. In combination, a housing provided with a pair of gas bags arranged substantially thereabove, the housing having angular plates embracing the lower outer portions, the plates having sockets, a pair of gravitating wings having hinge members hinged in the sockets, the upper and lower portions of 10 the sockets constituting means for limiting the wings in substantially horizontal and

vertical positions, the wings adapted to be entirely free to vibrate freely between the horizontal and vertical positions, when the housing is traveling in an undulated line. 15

In testimony whereof I have signed my name to this specification in the presence of two subscribing witnesses.
